CLAIM

The ornamental design for a two-jaw puller, as shown and described.

DESCRIPTION

FIG. 1 is a top perspective view of a two-jaw puller, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof;

FIG. 6 is a bottom plan view thereof;

FIG. 7 is a cross-sectional view thereof, taken along line 7-7 of FIG. 2;

FIG. 8 is a cross-sectional view thereof, taken along line 8-8 of FIG. 2; and,

FIG. 9 is a cross-sectional view thereof, taken along line 9-9 of FIG. 2.

The broken lines in the drawings illustrate portions of the two-jaw puller and form no part of the claimed design.
